UNITED STATES PATENT OFFICE.

ALBERT G. ELVIN, OF SOMERVILLE, NEW JERSEY, AND SAMUEL D. ROSENFELT, OF CHICAGO, ILLINOIS.

FIRE-DOOR APPARATUS.

1,186,978.

Specification of Letters Patent. Patented June 13, 1916.

Application filed September 13, 1913. Serial No. 789,645.

To all whom it may concern:

Be it known that we, ALBERT G. ELVIN and SAMUEL D. ROSENFELT, both citizens of the United States, and residents, respectively, of Somerville, in the county of Somerset and State of New Jersey, and of Chicago, in the county of Cook and State of Illinois, have jointly invented a certain new and useful Improvement in Fire-Door Apparatus, 10 of which improvement the following is a specification.

This invention relates to apparatus for operating fire doors of locomotive boilers, and other furnaces, and has for its object to 15 provide an improved fluid pressure operated apparatus of this character in which the furnace doors are pivoted to swing laterally and vertically in the opening movement, and to close by gravity.

20 The improvement claimed is hereinafter fully set forth.

In the accompanying drawings: Figure 1 is a front elevation of a fire door apparatus embodying our improvement, the motor cylinder being indicated in longitudinal section; Fig. 2, a transverse section of the same applied to the fire opening of a locomotive boiler; Fig. 3, a plan or top view of the motor cylinder and the operating connections; and, Fig. 4, a transverse section of the motor cylinder and illustrating a modification in the means for supporting the same.

According to the construction shown in 35 the drawings, our invention is exemplified as applied to a locomotive boiler having a door frame, 1, suitably mounted upon a rear sheet, 2, of the fire box, and surrounding the fire box opening, 3. The door frame is provided with an extension, 1^a, to which is bolted the cylinder, 4, of the door motor, preferably located horizontally and directly above the middle of the fire door opening. The opening is covered by the pair of doors, 40 45 10 and 11, which meet together upon the vertical center line of the opening, and are pivoted to swing laterally and vertically upon the respective pins, 7 and 8, which are mounted in recesses in the frame extension, 1^a, at the back, and in hollow bosses, 21, of the plate, 20, at the front, which plate may be formed as an integral extension of the cylinder casting, 6.

The pivoted arms of the doors, 10 and 11, 50 55 are provided with the respective gear seg-

ments, 12 and 13, which mesh together, and both doors are thus operated by means of the link, 14, pivotally attached at one end to the lug, 12^a, and at the other end to a pin, 15, carried by the piston, 6, and extending 60 through a horizontal slot in the side of the motor cylinder, 4. One end of the cylinder is closed by the cap, 5, and the piston is operated by fluid pressure admitted through pipes, 24 and 25, and controlled by the valve, 16, which may be of any suitable construction, preferably operated by a pedal device acting on the stem, 19.

When the operator desires to open the furnace doors for firing, or other purposes, he 70 opens the valve, 16, thereby admitting fluid into the cylinder, where it acts on the piston, 6, moving the same to the right, and, through the connecting link and segmental gears, swings the doors upward on their pivots to 75 the open position, in which the doors remain as long as the valve, 16, is held open. When the valve is released and closed, the fluid exhausts from the cylinder, and the doors close 80 by gravity, the outlet passage for the exhaust being restricted to prevent slamming of the doors.

For the purpose of operating the doors by hand whenever desired, we provide a hand lever, 18, which is curved around the door opening and provided with a straight shank, 18^b, at its upper end, and a handle, 18^a, at its lower end. The shank is pivoted loosely on the pin, 7, of the door, 10, and is adapted to engage a boss or lug, 17, formed on said door in such a manner as to swing the door up to its open position when the lever is pulled up by the handle, 18^a. This movement is also transmitted through the geared segments and link to move the piston out, 90 and open the other door, 11, at the same time. In order to hold the door open in different positions, the plate, 20, may be provided on its rear face with a number of notches located at desired points, such as 95 31 and 30, and adapted to engage the lever, 18, and hold the same in such position. The lug, 17, is preferably formed with an inclined surface engaging the lever, 18, in such a manner as to tend to deflect the same outward toward the notches on the rear of the plate when the lever is pulled upward by the handle, the looseness of the bearing of the lever upon the pin readily allowing for 100 105 such deflection. One of the notches, 31, is 110

located so as to latch the door open slightly for draft purposes and preventing the formation of smoke when the locomotive is standing at a station, while another notch, 5 30, is located at or near the end of the movement of the lever in order to latch the door fully open when desired. If the door should be standing latched by the hand lever in its partly open or draft position, when the controlling valve is opened for operating the fluid pressure motor, the piston acting through the rack and segment swings the door away from the hand lever to its wide open position, the hand lever at the same 10 time dropping out of said notch swings back by gravity to its stop, at its normal closed position. Then upon releasing the controlling valve, the door closes in the usual way. If, however, the door is latched by the hand lever, in its wide open position at the time 15 that the controlling valve is opened, there will be no movement of the door as the piston is at the end of its stroke and the latch cannot be released by the fluid pressure. 20 25 This relation between the fluid pressure operating mechanism and the manually operated device is also important as a safety feature, since it prevents an accidental closing of the doors by the movement of the valve or the failure of the fluid pressure, when the doors are manually set to the open 30 position for the purpose of entering the firebox for inspection or repairs. It also enables the fireman to operate the doors by 35 fluid pressure in the usual manner, even when the doors are set at the intermediate draft position.

In Fig. 4, we have shown a modified form 40 of pivot pin on which the door or doors may be hung, and also adapted to support the motor cylinder. In this construction, the pin, 7^a, is provided with an intermediate or middle portion of comparatively large diameter, on which the door, 10, and 45 the hand lever, 18, are mounted, and two reduced end portions forming shoulders against one of which the frame, 1^a, is rigidly clamped by a nut on the rear end of the pin, the other reduced end extending 50 through the cylinder flange or plate, 20^a, which is rigidly clamped against the other shoulder of the pin by the nut on its front end. In this way the pin is firmly secured

to the frame and the cylinder is rigidly supported on said pin or pins. The cylinder may then be taken down, without disturbing the door, by simply uncoupling the link, and removing the nuts from the pins. A bracket arm, 1^b, bolted to the frame, may be employed for bracing the top of the cylinder, if desired. 55 60

Having now described our invention, what we claim as new and desire to secure by Letters Patent is:

1. In a fire door apparatus, the combination of a door frame, a door pivoted at its upper side to swing laterally and vertically, a motor cylinder mounted above said door and having a depending flange or plate, a piston in said cylinder with connections for operating said door; and a pivot pin for the door, mounted in said frame and in the cylinder plate. 65 70

2. In a fire door apparatus, the combination of a door frame, a door pivoted at its upper side to swing laterally and vertically, a motor cylinder mounted above said pivot and having a depending flange or plate, a piston with connections for operating said door, and a pivot pin for the door, mounted 75 80 at the rear end in the frame, and at the front end in the cylinder plate.

3. In a fire door apparatus, the combination of a door frame, a pivot pin rigidly mounted in said frame, a door pivoted on 85 said pin, a motor cylinder having a flange rigidly secured to and supported on said pivot pin, and a piston and connections for operating said door. 90

4. In a fire door apparatus, the combination of a door frame, a pivot pin rigidly secured at its inner end in said frame, a door pivoted to swing laterally and vertically on said pin, a motor cylinder having a downwardly projecting flange rigidly secured to and supported on the outer end of 95 said pin, and a piston and connections for operating said door.

In testimony whereof we have hereunto set our hands.

ALBERT G. ELVIN.
SAMUEL D. ROSENFELT.
